Patented Dec. 28, 1915.

UNITED STATES PATENT OFFICE.

SAMUEL KAHN, OF NEWARK, NEW JERSEY.

BLOW-OFF VALVE.

1,166,221.

Specification of Letters Patent. Patented Dec. 28, 1915.

Application filed March 13, 1915. Serial No. 14,197.

To all whom it may concern:

Be it known that I, SAMUEL KAHN, a citizen of the United States, and a resident of Newark, in the county of Essex and State of New Jersey, have invented a new and Improved Blow-Off Valve, of which the following is a full, clear, and exact description.

This invention relates to devices for use in connection with pneumatic tires or other compressed air containers and has particular reference to means for charging such containers with a predetermined amount or pressure of air.

More definitely stated, among the objects of the invention is to provide a valve structure of a compound nature embodying the characteristics of the now well known check valve to retain the air within the tube and having also an auxiliary valve mechanism permitting any excess pressure over the predetermined degree to be discharged or dissipated while the first mentioned check valve becomes seated, retaining the precise desired amount of pressure within the tube.

Another object of the invention is to provide a peculiar and efficient means for adjusting the auxiliary valve to insure its operation within predetermined maximum and minimum limits.

A further object of the invention is to utilize the facilities above mentioned in connection with means for testing the degree of pressure within the tube.

A still further object of the invention is to improve the facilities for detachably connecting the testing device to a fixed spud or nipple.

The foregoing and many other objects of the invention will hereinafter be more fully described and claimed and illustrated in the drawings forming a part of this specification in which like characters of reference indicate corresponding parts in all the views, and in which—

Figure 1 is a vertical sectional view of one form of my improvement; Fig. 2 is a side elevation of the upper portion of the nipple shell looking toward the right in Fig. 1; Fig. 3 is a transverse sectional view on the line 3—3 of Fig. 1; Fig. 4 is a similar view on the line 4—4 but on a scale smaller than Fig. 1; Fig. 5 is a view similar to Fig. 1, parts being in elevation, and indicating slight modifications in detail; Fig. 6 is a view corresponding to Fig. 2 but taken as looking toward the right in Fig. 5; Fig. 7 is

a transverse section on the line 7—7 of Fig. 5; and Figs. 8 and 9 are vertical sectional details of modified forms of the invention described below.

The several parts of this device may be made of any suitable materials, and the relative sizes and proportions, as well as the general design of the mechanism, may be varied to a considerable extent without departing from the spirit of the invention hereinafter more fully set forth and claimed. I wish it to be understood furthermore that the term "tire" as used herein is to be interpreted as typical of any chamber or other container which may be charged with compressed air or the like; also the terms "vertical" and "horizontal" which may be employed in the description of the drawings attached hereto are to be interpreted as being relative only and not in a limiting sense in view of the fact that the parts are all operative irrespective of the position thereof with respect to the vertical.

Referring again to Fig. 1, I show at 10 a fragment of a pneumatic tire to which is secured a shank 11 constituting the fixed portion of the valve nipple. Said shank has a groove 12 into which the tire 10 extends between a head 13 on one side and a lock nut 14 on the other side and turned down upon the threaded portion 15 of the shank. A collar 16 is held against the lock nut by means of another nut 17 and bears at its periphery against the rim 18. The rim and felly 19 are bored as usual to accommodate the valve mechanism.

The shank 11 is bored at 20 and has secured rigidly to its outer end a tubular shell 21. The enlarged bore of the shell is formed at its lower end with screw threads 22 and above the threads it is tapered upwardly, the smooth tapered surface coöperating with the tapered extreme upper end 23 of the main shank. This connection makes an absolutely airtight joint and one which is strong and rigid. The exterior surface of the shell in which the taper is formed is screw threaded, as shown at 24, terminating in a shoulder 25. A lock nut 26 of peculiar construction coöperates with the screw threads 24 to lock the shank and shell as a unit to the rim and felly. This lock nut has a cavity 27 having internal cam surfaces 28. The cavity forms a receptacle for the lugs 29 at the base of a dust cap 30. Said lugs are slipped directly downwardly into or

- through spaces 31, and then by giving the dust cap approximately a quarter turn, the lugs 29 interlock with the cam surfaces 28 and beneath the overhanging lips 32 of the lock nut 26. At 33 I show a rubber gasket co-operating with a metal washer 34 between the dust cap base and the main portion of the lock nut to positively exclude moisture from the valve mechanism.
10. Adjacent the shoulder 25 is a reduced shoulder portion 35 having an external screw thread for the attachment of a cap 36 which will be termed hereinafter "air cap" to distinguish it from other caps. The air cap at 15 its closed outer end is fitted with a gasket 37 held in an undercut socket by means of a stud 38 arranged in the axis of the cap and having a shallow cavity in its upper end. The air cap 36 constitutes an airtight closure 20 for the valve shank and shell and is removed from the shoulder 35 when the valve is to be inspected or the tire is to be recharged.
- The upper end of the shell adjacent and above the shoulder 35 is still further reduced 25 forming a cylindrical nipple 39 having its extreme upper end threaded either internally or externally or both for the attachment of a pressure device or the like. Between the threaded end of the nipple and the shoulder 35 the outer surface of the nipple is smooth and cylindrical, and upon the same is slidably fitted a sleeve 40. A bayonet slot 30 41 is formed in one wall of the nipple and a pin 42 extends through the lower end of the sleeve 40 through said slot. The pin, therefore, limits the extent of movement, 35 up or down, of the sleeve along the nipple. Within the tapered cavity formed in the lower portion of the shell 21 is snugly seated 40 a valve seat 43 tapered to correspond to the aforesaid taper and provided with a plurality of vertical parallel ports 44 shown herein as eight in number. These ports are arranged with their upper ends in a circle 45 and communicating in the same annular space between a pair of concentric ridges 45 against which an upwardly movable blow-off valve 46 is normally seated. This valve 46 includes a rubber or similar packing 47 adapted to bear against the ridges 45 and closing the space into which the ports 47 lead. The valve has an upwardly extending collar 48 serving as a guide for the valve along a stem 49 secured by the valve seat 43.
- 50 The valve 46 is held normally seated by means of a comparatively strong spring 50 surrounding the collar 48 and bearing at its lower end upon the valve and at its upper end against an adjustable head 51 fitted upon 55 the upper portion of the stem 49 and against whose upper end a preliminary adjustment nut 53 is adapted to bear, said nut being threaded upon the extreme upper end of the stem 49 prior to assembling the device.
- 60 65 Among the uses of this nut 53 may be noted

that of determining the proper strength of the spring 50 for use in connection with the valve of a predetermined strength or registry. The aforesaid pin 42 is tapped into the head 51 and hence causes the movement of 70 the head downwardly with the sleeve 40, thereby placing the spring 50 under greater tension corresponding to the vertical length of the bayonet slot 41. When the sleeve 40 is thus depressed, it may be locked in the 75 lower position by giving it a slight rotation, bringing the pin 42 into the angular portion of the slot.

The threaded upper end of the stem 49 projects into a recess 54 at the upper end of the nipple 39 and a nut 55 secured thereto forms a seat or cup in which is supported the lower end of a light spring 56 surrounding the stem 57 of the check valve 58. The upper end of the spring 56 is held in place 80 by means of a cap 58' within the nipple. Said cap is provided with a plurality of ports 59 extending upwardly therethrough and diverging from points close to the stem 57. Said stem 57 extends freely through a central bore 60 extending through the stem 49 of the blow-off valve 46. The check valve 58 includes a gasket 61 held normally seated by virtue of the spring 56 against a nozzle 62 formed on the lower surface of a plug 63. 90 The plug and nozzle have a central bore 60' corresponding to and aligning with the stem bore 60 and leading into a distributor chamber 64 and communicating with the lower ends of all of the ports 44. The plug 63 has a tapered periphery and is fitted snugly air-tight into the taper of the shell 21 against the valve seat 43.

The operation of the device thus far described may be briefly stated as follows: 105 Upon removal of the dust cap 30 and the air cap 36, air supply connection may be made with the threaded end of the nipple 39 in any convenient manner such, for instance, as the flexible tube leading from an air 110 pump or reservoir (not shown). Air under pressure may then be admitted downwardly through the nipple, such air passing either through or around the cap 58' and through the bores 60 and 60'. This air pressure unseats the check valve 58 downwardly against the force of the spring 56, allowing the air to enter the tire 10. This action corresponds, generally speaking, to the usual action of a tire nipple check valve. With the 115 force of the spring 50 adjusted to correspond to the predetermined desired internal pressure for the tire, when such pressure is reached by the action of the air pump or air pressure supply means, no greater pressure 120 of air can be made in the tire for the reason that the excess pressure over the predetermined required amount or degree will react upwardly through the ports 44 and unseat the blow-off valve 46 and be discharged to 125 130

the atmosphere through the vent or vents 65 formed radially through the lower end of the nipple. Since the excess pressure becomes thus dissipated through the vents 65, the check valve 58 will promptly close due to suction and the spring 56, and the blow-off valve 46 will remain open and functional so long as the inwardly directed air pressure continues. The operator, upon hearing the hiss of the escaping air, will be apprised that the required degree of pressure within the tire is reached.

By way of illustration it may be assumed that the spring 50 is so designed that when the head 51 is adjusted as shown in Figs. 1 and 2, the excess air will blow off when an internal pressure of seventy pounds per square inch is reached, and when the sleeve 40 is pushed downwardly to lock the pin 42 in the angular portion of the slot 41, the pressure required to unseat the valve will be increased to eighty pounds. Assuming, then, that the tire is to be inflated to eighty pounds, the sleeve 40 will be forced downwardly and locked as just stated while the air is being introduced. When the eighty pounds pressure is reached in the tire, the excess pressure will be dissipated and the check valve will be closed, retaining within the tire the precise pressure required. In this connection it will be noted that while an ordinary safety or blow-off valve for the release of excess pressure after being unseated subjects the pressure fluid to an increased effective area, the ordinary result is that the internal pressure will be lowered to a considerable extent, say five or ten pounds, below the required pressure or the point at which the blow-off takes place. In this invention, however, the check valve seating promptly at the moment the blow-off valve becomes functional, there is no possibility for the slightest lowering of the internal pressure below the point desired or to which it is adjusted or designed.

In the ordinary operation of pneumatic tires a certain range of pressures is provided for, and assuming that such range, used in the same illustration as given above, is of from seventy to eighty pounds and the operator wishes to test his tire to see whether at least seventy pounds of pressure exists, all he needs to do to make such test at any time is to remove the dust cap and air cap from about the nipple, and with the sleeve 40 and pin 42 adjusted upwardly, as shown in Figs. 1 and 2, he may apply the air cap bringing the stud 38 with its cavity bearing upon the cap 58' and with the gasket 37 coming into contact with the end of the nipple sealing the nipple against the discharge of air therefrom. If, now, the operator observes the hiss of the discharge of air through the vents 65, he will know immediately that the internal pressure is above the minimum pre-

determined degree of seventy pounds and hence satisfactory. If, however, the unseating of the check valve 58 will not occasion a discharge through the auxiliary valve and vent 65, the operator will immediately know that the internal pressure has fallen below the required minimum of seventy pounds and that the tire requires re-inflation to bring it up again to the required point. To prevent air from passing downwardly from the recess 54 around the stem 49, I provide a packing washer 66 locked in place by the nut 55. The ports 59 formed through the cap 58' registering with the upper end of the bore 60 prevent the cap from sealing the upper end of the bore. The combined area of the ports 59 is preferably approximately the same as that of the bore 60, and if the ports are formed too large, one or more of them may be plugged, if desired, to properly proportion the relative areas in any particular case.

That form of the invention shown in Fig. 5 is substantially the same as that already described with respect to the main and blow-off valves 58 and 46 and the parts which control their operation. This form of the device, however, typifies its use as a detached part or structure capable of being carried in one's pocket or tool box as a feature separate from the tire nipple. The device of Fig. 5, however, is adapted to be applied to any standard nipple or that portion corresponding to the nipple 39 with a resulting operation substantially similar to that already set forth in detail. Considering, then, for the purposes of this explanation, the nipple 39 as exemplifying any standard tire nipple with or without the check valve 58 within the same, the shell 21' may be quickly secured to the nipple 39 with the rim or end of the nipple abutted snugly against a washer 67 by means of the quick attaching and detaching means shown in Figs. 5 and 7, the same including a coupling body 68 in which are slidably fitted a pair of radially movable blocks 69 having their inner ends threaded at 70 to correspond to the threads on the nipple. The coupling body 68 is surrounded by a thimble 71 secured to the body by means of a pin and slot connection 72, the lower edge of the thimble bearing inwardly against the beveled outer ends 73 of the blocks when the thimble is forced downwardly. When the thimble is elevated, however, the blocks are free to slide apart far enough for the nipple 39 to slip freely upward into engagement with the washer 67. The radial movement of the blocks, however, is limited in both directions by means of pins 74 carried by the blocks and movable in radial slots 75 formed in the lower end of the body 68. To apply the device, therefore, to a standard nipple, the thimble 71 being elevated, the body and shell tapped

therein are pushed directly upon the nipple, bringing the end thereof against the washer 67. The thimble then is forced directly downwardly, causing the blocks to move inwardly into threaded engagement with the nipple threads, making a substantially airtight connection, but by giving the device as a whole a slight rotation if necessary, the connection is rendered absolutely airtight without a moment's loss of time and the connection is secure so long as the thimble remains in its depressed position. To remove the coupling or device, therefore, all that is necessary is to simply pull up on the thimble with one's fingers, and such movement being continued will carry with it the entire device since the hold between the blocks and the nipple ceases by reason of the outward movement of the blocks.

20 The body 68 carries a stud 38' which serves to unseat any check valve carried within the nipple to which the device may be applied as above described, and after the device is attached it may be used as a blow-off charging device for the tire or as a testing device in substantially the same ways that are described above in connection with Fig. 1. In this form of the invention the pin 42 extends through a slot 41' formed through the shell 25' and secured in the head 51 as above described, but the outer end of the pin is carried by a sleeve 40^a which is actuated downwardly to increase the tension of the spring 50 by another sleeve 40^b. The sleeve 40^b is connected to the shell 25' by means of pins 76 projecting into a spiral groove 77 formed in the outer surface of the shell 25'. The effective position of the sleeve members with respect to each other and the spring is determined by certain graduations formed upon the adjacent ends of the sleeve members and indicated as including a point 78 carried by one member and co-operating with a plurality of notches 79 formed in the other. In other words, by a rotation of the sleeve 40^b in a clockwise direction, the pins 76 will cause the sleeve 40^a and the head 51 to move downwardly according to the pitch of the groove 77 as determined by the extent of such rotation. As indicated in Fig. 6, the sleeve members may be graduated according to any desired pressure, the illustration indicating, for example, pressures ranging from sixty to eighty pounds. The threaded nipple 39' is adapted to be sealed by means of an air cap 36' screwed thereon.

That form of the invention indicated in Fig. 8 is designed primarily for use in connection with a stationary compressed air supply as, for instance, in a garage. The structure includes a nipple 39^a for connection with the supply hose (not shown), and through which nipple is passed a tubular stem 49' through which the compressed air

is carried downwardly to the support or valve seat 43'. A check valve 80 co-operates with a valve seat 62' formed in the support 43'. When the check valve 80 is seated, as is the condition normally under the pressure of the fluid approaching the same through the nipple, it prevents the loss of the air supply from the storage tank. The support 43' is recessed at 64' making a discharge chamber communicating with all of the ports 44 leading upwardly into the annular space between the concentric valve ridges 45 upon which is seated the blow-off valve 46, said valve being normally closed by the spring 50 until the predetermined degree of pressure is obtained within the tire, when the excess pressure will cause the valve 46 to be unseated and a discharge to be made through the vent 65.

The stem 57' leading downwardly from the check valve 80 co-operates with and unseats the usual check valve in the tire, and since the movement of such check valve is less than the length of the projecting end of the stem 57', the same pressure will cause the check valve 80 to unseat upwardly as shown in Fig. 8. This immediately provides free passage for the air supply downwardly through the tube 81, filling the tire up to the desired pressure determined, as before, by the strength of the spring 50. When this pressure is reached, the air pressure acting through the chamber 64' and ports 44 will cause the unseating of the blow-off valve and the dissipation of the excess pressure. The air is free to pass at all times from the tube 81 to the chamber 64' through ports 82. It will be sufficient, therefore, that this construction for automatic delivery of air pressure from a storage tank to a tire will be operative up to a certain pressure and will then automatically blow off, giving a signal to the operator that the required pressure has been received and preventing the over-charging of the tire.

Fig. 9 is a somewhat diagrammatic view indicating a further modification and showing a check valve 58' seating upwardly against the valve seat 62 and preventing the upward flow of air from the tire when the required degree of pressure is received therein. The blow-off valve 46 is held normally seated upon a valve seat 43' under the force of the spring 50, the other end of the spring acting against a head 51' movable through a pin or finger piece 42' to provide the maximum and minimum pressure points as previously explained. The valve stem 48' is connected through a rocking lever 83 to a valve 84 held normally open by the spring 50. The main support 43^a is bored at 85 to permit the passage of air downwardly to the tire directly and also in the other direction to unseat the blow-off valve when the required pressure is reached, the

valve 84 closing promptly, however, and stopping the flow through the bore or port 85.

It will be seen that in all forms of the invention I provide a safety blow-off valve to indicate that the required degree of pressure is reached in the tire and automatically providing for the dissipation or discharge of the excessive pressure, and that in all forms of the invention I provide a valve seat or supporting structure with which a plurality of valves coöperate to control the flow of air through the support in either or both of two directions.

15 As shown especially in Fig. 1, the check valve 58 is locked upon its stem with respect to the gasket by means of a conical nut whose largest diameter is approximately equal to the diameter of the check valve 20 seat bore. Said nut being conical enters freely within the valve seat, bringing the gasket directly against the seat in such a manner that there is no possibility for the internal pressure to cause the cupping of the 25 gasket and hence the check valve readily unseats when pressed downwardly.

Referring again to Fig. 5, it will be observed that since this structure is designed to be used as a pressure gage or testing device 30 for tires previously inflated, the air cap, when in normal position as shown, acts to unseat the check valve 58; hence, by applying this structure directly to a valve nipple, the check valve being open will not 35 obstruct the passage of air from the tire through or past the blow-off valve. I wish it to be noted also that the threaded inner ends of the blocks 73 are tapered slightly so as to facilitate the introduction of the tire 40 nipple upwardly between them.

I claim:

1. A blow-off valve, comprising a substantially straight body, a check valve, a blow-off valve, the valves being arranged longitudinally in the body, one above the other, the check valve being at the exit side of the body and separated from the blow-off valve by an air-tight device, whereby, when the check valve is closed, the compressed air is 50 excluded from the blow-off valve.

2. In a device of the character set forth, the combination of a valve casing, supporting means fitted therein and provided with a plurality of passageways for the passage 55 of air in relatively different directions therethrough, said supporting structure having at one end a pair of spaced annular ridges, certain of said passageways communicating with the space between the ridges, and a blow-off valve seated normally upon both 60 of said ridges and closing the space between them.

3. In a device of the character set forth, the combination of a valve shell, supporting 65 means therein providing a plurality of valve

seats coaxially arranged, a tubular stem extending upwardly from the supporting means, means to introduce an air supply through said stem, a check valve coöperating with the lower portion of the supporting means and opened by said air supply up to a predetermined degree of pressure, said supporting means having upwardly directed ports in communication with the air supply, a blow-off valve surrounding said stem and subject to the action of air through said ports, and a spring of predetermined strength surrounding said stem and acting to normally hold the blow-off valve seated but permitting the excess pressure above the predetermined degree to unseat the blow-off valve and be discharged into the atmosphere, the check valve automatically closing simultaneously therewith and retaining the full predetermined amount of pressure below the same.

4. In a device of the character set forth, the combination of a valve casing having a tapered interior, supporting means fitted in said taper and providing upper and lower valve seats, said supporting means having a chamber formed therein and a plurality of ports leading upwardly from said chamber, the upper valve seat constituted by a pair of spaced ridges between which said ports pass, a blow-off valve seated upon said ridges and preventing the passage of air from said space up to a predetermined degree of pressure, and means to control the flow of air through said supporting means.

5. In a device of the character set forth, the combination of a valve casing having a tapered interior, a valve seat having a similar taper fitted airtight within the casing, said valve seat having a plurality of longitudinal ports, a plug likewise fitted in the casing against one end of the valve seat, said plug having a chamber communicating with said ports and a downwardly projecting tubular valve seat, a check valve coöperating with the latter mentioned valve seat, a blow-off valve coöperating with the other end of the first mentioned valve seat, and means to variably control the action of the blow off valve upon its seat according to various predetermined degrees of pressure.

6. In a device of the character set forth, the combination of a valve shell, a valve seat fitted airtightly therein, means to control the downward movement of air through said valve seat in one direction up to a predetermined degree of pressure, a valve seated normally downwardly upon the valve seat but movable therefrom under the upward force of air through the valve seat when said degree of pressure is exceeded, a spring acting upon the valve at one end, a head slideable in the shell and coöperating with the other end of the spring, and a pin extending through

the shell into the head for determining the position of the head and the force of the spring in predetermined quantities.

7. In a device of the character set forth, 5 the combination of a valve shell having a reduced upper end, a valve seat in the lower portion of the shell, said valve seat having a central passageway for air and other passageways parallel thereto, means to control 10 the downward passage of air through the valve seat in one direction up to a predetermined degree of pressure, a blow-off valve coöperating with the valve seat and normally preventing upward passage of air 15 through the latter mentioned passageways but adapted to unseat upwardly under pressure above the said degree, a head slideable in the reduced extension of the shell, a spring of predetermined strength acting between 20 the head and the valve, a shell having a slot adjacent the head, a pin extending through the slot and fitted in the head, and a sleeve fitted upon the shell extension and adjustably determining the position and effect 25 of the spring.

8. In a device of the character set forth, 30 the combination of a valve shell, means within the shell to control the passage of air supply downwardly therethrough up to a predetermined degree of pressure in the tire, a blow-off valve acting in the other direction automatically to discharge pressure above the predetermined degree aforesaid, an attachment body secured to the shell and provided with recesses, a pair of radially movable blocks fitted in said body and having gripping means on their inner ends and longitudinally arranged guide pins engaging the recesses of the body, and a thimble 35 slideable upon the body to force the blocks directly into engagement with the tire nipple.
9. In a device of the character set forth, 40 a shell, a valve seat in the shell and having a central opening, an annular groove in one face and ports extending through the same and opening into the groove, a sliding and spring pressed blow-off valve for engaging said seat, a second valve seat adjacent the first seat and having an opening in alignment with the central opening of the first 45 seat and a chamber in one face and into which open the ports of the first seat, and a

check for the second seat and having a stem extending through the said valve seats.

10. In a device of the character set forth, a shell, a valve seat in the shell and having a central tubular stem, an annular groove in one face and ports extending through the same and opening into the groove, a sliding and spring pressed blow-off valve mounted on the tubular stem, a second valve seat adjacent the first valve seat and having a central opening and a chamber in one face around said opening, and a check valve for the second seat and having a stem extending through the opening of the second seat into the tubular stem of the first seat. 55 60 65

11. In a device of the character set forth, a shell having a port in its side, an adjustable head in the shell, a valve seat in the shell and between which and the head the port is located, said seat having a central tubular stem and an annular groove in one face and ports extending through the same and opening into the groove, a blow-off valve mounted to slide on the stem of the said seat, a spring surrounding the said tubular stem between the head and valve, a second valve seat engaging the first valve and seat and having a chamber in its face next to the first seat and provided with a tubular projection on its other face, and a check valve engaging the said tubular projection and having a stem extending through the same into the tubular stem of the first valve seat. 70 75 80 85

12. In a device of the character set forth, a shell having a bayonet slot, a head in the shell, a sleeve slideable on the shell, a pin secured to the sleeve and head, said pin working in the slot of the shell, a valve seat in the shell and having a tubular stem extending through the head and having its projecting end threaded, a nut on the said threaded end, a blow-off valve mounted to slide on the valve seat, and a spring surrounding the stem of the valve seat between said seat and the head. 90 95

In testimony whereof I have signed my name to this specification in the presence of two subscribing witnesses.
